UNITED STATES PATENT OFFICE.

JEWETT L. NORRIS, OF COLUMBUS, OHIO, ASSIGNOR OF ONE-HALF TO
THOMAS H. RICKETTS, OF SAME PLACE.

TROUSERS-STRETCHER.

SPECIFICATION forming part of Letters Patent No. 680,269, dated August 13, 1901.

Application filed May 31, 1900. Serial No. 18,541. (No model.)

To all whom it may concern:

Be it known that I, JEWETT L. NORRIS, a citizen of the United States, residing at Columbus, in the county of Franklin and State 5 of Ohio, have invented a certain new and useful Improvement in Trouzers-Stretchers, of which the following is a specification.

My invention relates to the improvement of trousers-stretchers; and the objects of my 10 invention are to provide a simple, inexpensive, and effective trousers-stretching device which can be conveniently supported on either face of a door, to provide improved means for the adjustable support and stretching 15 of the trousers between the stretcher-sections, and to produce other improvements, the details of construction and arrangement of parts of which will be more fully pointed out hereinafter. These objects I accomplish 20 in the manner illustrated in the accompanying drawings, in which—

Figure 1 is a plan view of the upper stretcher-section. Fig. 2 is an end view of the same. Fig. 3 is a central transverse section on line xx - xx 25 of Fig. 1. Fig. 4 is an under side view of the central portion of the lower stretcher-section. Fig. 5 is a plan view of said lower stretcher-section, and Fig. 6 is an end view of the lower stretcher-section.

Similar numerals refer to similar parts 30 throughout the several views.

In carrying out my invention I employ an upper stretching-section, which in the manner hereinafter described is adapted to be secured to either the inner or outer face of a 35 door or other similar surface. Of this upper stretcher-section 1 represents the base or attaching bar, which has its upper side covered with a strip of felt or similar material 2. The 40 bar 1 is provided on its under side with a central transverse attaching bracket or plate 3, one of the projecting ends of which is provided with a screw or nail opening 3^a , and the opposite projecting end of which is provided 45 with an elongated or slotted opening 3^b . Projecting outward from each end of the base-bar 1 and inclining slightly upward therefrom are bearing or bracket arms 4.

5 represents the binding-bar of the upper 50 section, which in the manner hereinafter described is adapted to fit loosely and swing be-

tween the bracket-arms 4, said binding-bar being oblong in cross-section. On each end of the binding-bar 5 I provide an end plate 6, the upwardly-projecting portion of which is 55 provided with a pin 7, these bearing-pins being journaled in openings in the outer ends of the bracket-arms 4. The bar 5 is preferably covered with felt or a similar cloth 8. Owing to the fact of the binding-bar being pivotally 60 connected with the arms 4 and these pivot-points being arranged eccentrically, as described, it is obvious that the normal tendency of the inner or binding surface of the bar 5 is to drop into a position parallel with 65 and in close proximity with the felt-covered surface of the base-bar. As indicated at 9 in Fig. 3 of the drawings, I may for the sake of providing space between the base and clamp bars for the accommodation of the 70 seams or hems of the trousers-legs cut away the outer side of the clamping-bar at the center thereof.

The above-described upper stretcher-section is adapted to be secured to a door, preferably the inner side of a closet-door, through the medium of a screw or screw-eye passing loosely through the opening 3^a of the attaching-plate 3 into the door and a suitable form of nail or screw passing loosely through the 80 slotted opening 3^b .

In further carrying out my invention I employ a lower clamping-section which is adapted in the manner hereinafter described to be 85 adjustably supported on a door at a point below the upper section. Of this lower section 10 represents the base or attaching bar, which is preferably shorter than the upper bar 1 and which, as prescribed for said upper bar, has its outer face covered with a strip of felt 90 11. The bar 10 has projecting outward from each end thereof a bearing arm or bracket 12, and between these brackets is arranged to swing, as hereinafter described, a binding-bar 13, the latter being of the substantially 95 half-round form in cross-section shown in the drawings. As prescribed for the binding-bar 5, the bar 13 is preferably covered with felt, as indicated at 14. Each end of the bar 13 is provided with an end plate 15, from which 100 projects eccentrically or at a point adjacent to the flat outer side of said bar a journal or

pivot pin 16, these pins being journaled in the outer ends of the brackets 12. The end plates 15 are also provided with projecting finger-pieces 17.

5 Affixed transversely to the central portion of the rear side of the base-bar 10 is a plate 18, said plate being provided with upper and lower outwardly-projecting guide lugs or ears 18^a, having oppositely-located openings 10 therein. This plate also has fulcrumed thereto a spring-actuated pawl or dog 19, the inner or toothed end of which is normally held in engagement with one of the teeth or notches of a toothed or notched rod 20, which passes 15 loosely through the openings of the lugs 18^a and which rod, as indicated more clearly in Fig. 5 of the drawings, terminates in end-attaching lugs 21, which are adapted to be secured to the face of a door at points in vertical alinement with the center of the upper bar 5.

The upper and lower sections of my device being secured to a door in the manner herein described, the trousers to be stretched have 25 their upper and wider portions, subsequent to one leg thereof being folded upon the other, inserted between the binding-bar 5 and base-bar 1 of the upper section, the said binding-bar being previously raised or turned away 30 from said base-bar. The binding-bar is automatically turned inward, when the trousers are slipped under and over the same and are firmly clamped between the felt-covered parts 1 and 5. This being accomplished, the lower 35 portions of the trousers-legs are inserted between the bars 13 and 10 and are clamped in this position by turning said bar 13 until its rounded felt-covered surface binds the trousers-legs into contact with the felt-covered 40 surface of the bar 13. The trousers thus clamped are then stretched or placed under desirable tension by pressing down with the palms of both hands on the bar 10 and allowing the pawl-tooth to spring into a new notch of said 45 rack-rod. In this manner the legs of the

trousers are not only firmly clamped in the upper and lower sections, but the same are firmly held in a stretched position, which results in pulling the wrinkles therefrom and imparting front and rear creases to the legs 50 thereof. Owing to the fact that the upper clamping-section is pivoted it is obvious that in case the upper portion of the trousers-legs are not so inserted as to cause the upper clamping-bar to cross the same exactly at 55 right angles with the direction of the length of the trousers-legs the upper binding-section may swing sufficiently on its pivot to compensate for such difference, with the result that the strain or tension on the rear 60 and front sides of the trousers-legs will be equalized.

From the construction herein shown and described it will be seen that a simple, reliable, and quickly-operated construction of 65 trousers-stretcher is produced which may be readily attached to an ordinary closet-door or similar surface.

Having now fully described my invention, what I claim, and desire to secure by Letters 70 Patent, is—

The trousers-stretcher herein described consisting of the upper bar mounted for pivotal movement, a clamp eccentrically mounted on said bar, to fold downward to clamp 75 the trousers, a vertically-disposed rod independent of the upper bar and having means for its attachment to a door, a lower bar mounted on said rod for sliding movement thereon and for pivotal movement on said rod 80 as a center, and a clamping-bar eccentrically mounted on said lower bar and movable in the direction opposite to that of the upper clamp to clamp the trousers, substantially as shown and for the purpose set forth.

JEWETT L. NORRIS.

In presence of—

A. L. PHELPS,
R. G. HESSONG.
